UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

SHOE-SEWING MACHINE.

1,124,195.

Specification of Letters Patent.

Patented Jan. 5, 1915.

Original application filed June 17, 1911, Serial No. 633,750. Divided and this application filed June 13, 1912. Serial No. 703,486.

To all whom it may concern:

Be it known that I, ARTHUR BATES, a subject of the King of Great Britain, residing at Leicester, in the county of Leicester, 5 England, have invented certain new and useful Improvements in Shoe-Sewing Machines; and I do hereby declare the following to be a full, clear, and exact description of the invention, such as will enable others 10 skilled in the art to which it appertains to make and use the same.

This invention relates to shoe sewing machines, and more particularly to shoe sewing machines of the type in which the stroke 15 of the needle is varied in accordance with changes in the thickness of the work, and in which the work is fed by an intermittently operating work-feeding awl or feed point.

20 The object of the invention is to produce a machine of this class having improved and simplified mechanism for actuating the awl, arranged to positively control the awl throughout its movement and to maintain 25 the feed substantially constant notwithstanding variations in the stroke of the needle.

With the above object in view, one feature of the invention contemplates the provision in a shoe sewing machine in which the stroke of the needle varies in accordance with changes in the thickness of the work, of an awl feed mechanism and operative connections between the same mechanism 35 and the needle, which connections are so arranged that the awl is always under positive control and its feed is maintained substantially constant notwithstanding variations of the stroke of the needle. The said operative 40 connections may comprise a linkage, of which one element is connected with the needle bar and is so disposed that its said connection is upon a dead center when the needle is at or approximately at the limit 45 of its penetrating stroke.

Further features of the invention consist of certain devices and combinations herein-after described and claimed, the advantages of which will be obvious to one skilled in the 50 art from the following description.

This application is a division of application Serial No. 633,750, filed June 17th, 1911.

In the accompanying drawings figure 1 is a side elevation, partly in section, of a sewing machine embodying the invention in 55 its preferred form; Fig. 2 is a view showing in detail the mechanism for effecting the work-feeding motion of the awl; Fig. 3 is a view similar to Fig. 2, but showing the parts in a different operative position; Fig. 60 4 is a detail view illustrating particularly the needle actuating mechanism, and showing the position which the parts assume when the needle reaches the limit of its upward stroke; Fig. 5 is a detail plan view of 65 the needle actuating mechanism.

In the machine as illustrated in the drawings, the rotatable horn 1 is arranged to be movable vertically to accommodate varying thicknesses of work and a stationary 70 abutment 2 is provided against which the horn clamps the work during such times as a stitch is in progress of formation. The needle-driving mechanism varies the extent of downstroke imparted to the needle and 75 by means of connections between the horn and the needle-actuating mechanism this extent is automatically corrected to maintain correct coöperative relationship between the needle barb and looper in the horn tip. To 80 insure that this variation shall correspond exactly with the thickness of the material, the abutment against which the horn clamps the work in caliperizing is located behind and in close proximity to the needle so that the 85 part of the work that is calipered will be that in which the stitch is in process of formation and not the part of the work that is in front of, or in rear of this position. This 90 has the advantage that the thread measured off from the supply will be in exact agreement with the thickness of that part of the work for which the stitch is being made.

To effect the vertical reciprocation of the needle bar the following mechanism is employed in this preferred embodiment of the invention: Upon the main shaft 3 of the machine is mounted an eccentric 4 (Fig. 1) the strap 5 of which has its arm 6 attached by a joint to the backwardly-extended arm 7 95 of a lever 7, 8, mounted to turn about a fulcrum 9 fixed upon the machine frame. The forwardly-extended arm 8 of the lever 7, 8 100 is coupled at 10 by a horizontally disposed

connecting link 11 with the upper end of another link 12 (hereinafter referred to as the anchor link) that is upstanding, being pivoted at its lower end 13 to a lever 14 fulcrumed at 15 toward the rear of the machine frame. This last named lever is coupled with the horn 1 so as to have its angular position controlled by the movement of the horn in compensating for the thickness 10 of the work. The connections between the lever 14 and the horn 1 comprise a rod 16 of which the upper end is coupled to the lever while the lower end is pivoted to a treadle lever 17; and a link 18 that connects 15 a sleeve 19, mounted upon an extension 20 of the horn, with the treadle lever 17. The connection between the sleeve 19 and the extension 20 is such as to permit the horn to turn with relation to the sleeve but compel 20 it to move vertically therewith. A spring 21 on the rod 16 tends to maintain the horn in its uppermost position.

To the horizontally-disposed connecting link 11 there is centered at 22 near its joint 25 with the anchor link 12, a pair of axially aligned twin links 23 which have their free ends connected at 24 to the pendant twin arms 25 of a bell crank lever 25, 26 fulcrumed at 27 upon the machine frame. The 30 forwardly-extended arm 26 of the bell crank lever 25, 26 is connected with the needle bar 28 by a suitable link 29.

In the operation of the needle mechanism arranged as set forth, the needle bar 28 is 35 reciprocated vertically from the eccentric 4 through the connections described; by which connections, it will be noted, the needle is maintained under positive control throughout its stroke. But according to the particular arrangement of the parts now to be 40 described, the upper limit of the path of the needle 30 is maintained always constant while the lower limit thereof varies in accordance with the thickness of the work.

45 To maintain constant the upper limit of the stroke of the needle bar, the pivots 24 (connecting the pendent twin arms 25 of the bell crank lever 25, 26, and the twin links 23) are substantially co-axial with the pivot 10 (connecting the horizontally-disposed connecting link 11 with the arm 8 of the lever 7, 8) whenever the needle bar 28 is at the said upper limit, the said pivot 10 being then located between the pivots 24 of the 50 twin links 23, as shown in Fig. 4. By this disposition of the parts, movement of the anchor link 12, due to alterations in the position of the horn 1 will swing both the horizontally-disposed connecting link 11 and 55 the twin links 23 connecting it with the pendent arm 25 of the bell crank lever 25, 26, about a common center, whereby the bell crank lever will remain in a constant position irrespective of variations in the position 60 of the anchor link 12 owing to variation in

the height of the horn 1. Thus, while these centers 10, 24, are in co-axial relationship the lever 14 connected with the horn may be turned on its center 15 without producing any movement of the bell crank lever 25, 26, 70 or the needle bar 28; and as this is the position of the parts when the machine is at rest, the horn 1 can be depressed for the removal of the work or for placing stock thereon without affecting the position of the needle 75 30.

At its upward extremity of movement, the pivot 10 connecting the horizontally-disposed link 11 to the arm 8 of the lever 7, 8, is brought into co-axial alignment with the 80 fulcrum 27 of the bell crank lever 25, 26, as shown in Fig. 1; and in this position, as will be apparent, vertical movement of the anchor link 12 would effect a turning of the bell crank lever 25, 26, so as to raise or 85 lower the needle bar.

By this arrangement, the lower limit of the movement of the needle bar is varied according to the thickness of the work through the position which the horn assumes when bearing against the work acting through the anchor link 12 as above described, it being understood that the movement imparted to the bell crank lever 25, 26, by the eccentric 4 and connections aforesaid 95 will be augmented or diminished according to the angular adjustment of the bell crank lever 25, 26 by the anchor link 12 and its connections.

The machine is provided with a feed point 100 or awl 31 (Figs. 2 and 3) which is secured to a pendent awl bar 32 coupled by a universal or Hooke's joint 33 to a lever 34 pivoted at 35 (see also Fig. 1) on the machine frame and provided with a roller running in 105 a cam groove on a cam 36 on the main shaft 3. The awl 31 is moved into and out of engagement with the work by this mechanism but is moved laterally to feed the work by connections from the needle bar 28. These 110 connections comprise a collar 37 secured to the needle bar and connected by a link 38 to a lever 39 pivoted at 40 upon the machine frame, which lever is also connected by a link 41 to a lever 42. The lever 42 is pivoted to the machine frame at 43 approximately at its center and has its lower arm connected with the awl bar. Conveniently the said connection comprises a block 44 mounted upon the lower arm of the lever 115 40 and engaging a slot 45 formed in the awl bar, the block being adjustable in a slot 46 along the lever so that the feeding stroke of the awl may be altered according to requirements.

To prevent the feeding stroke of the awl from being altered by the variation of the penetrating stroke of the needle owing to differences in the thickness of the work, the disposition of the link 38 that joins the col. 120 125 130

lar 37 on the needle bar with the lever 39 is such that at or approximately at the end of the penetrating stroke of the needle the pivotal connection between the link 38 and 5 the collar 37 is upon a dead center and thereby the differences in the vertical position of the needle bar, due to the alteration of its stroke, will have a negligible effect upon the lever 42 that imparts the feeding movement 10 to the awl. In place of this particular system of linkage herein described, any other suitable arrangement of parts may be employed, by which, as in the foregoing construction, the awl is always under positive 15 control and its feed maintained substantially constant notwithstanding variations of the stroke of the needle.

In a machine of this type as usually arranged, the work is clamped between the 20 horn 1 and the abutment 2 and according to this invention the abutment is so located as to measure or caliper, in conjunction with the horn, the thickness of the work at the point at which the needle is operating, so 25 that the length of thread required for the stitch is accurately determined. For this purpose the abutment is mounted on the frame of the machine close to and behind the needle (Fig. 1) and is of such form as to 30 have its contacting surface in close proximity to the needle. Conveniently the abutment is adjustably received in a split socket 47 and is secured in its correctly adjusted position by a bolt 48 that passes through 35 lugs projecting from the said socket. The abutment may act also as a work guide against the raised channel of the work and in combination with the awl feed constitute means for turning the boot automatically 40 when the toe or other curved portion of the boot is being sewn, by offering some resistance to the work (while it is being fed) toward the center about which it is required to turn.

45 In the machine illustrated in the drawing mechanism is provided for turning the horn when the toe or other sharply curved portions of the shoe are being operated upon, in order to assist the operator in the presentation of the work to the sewing devices. Inasmuch as this mechanism forms no part of the present invention and is fully described in application Serial No. 663,750, referred to above, no detailed description thereof is 50 made in this application.

55 While the invention has been illustrated and described as embodied in a machine provided with a shoe supporting horn and a vertically reciprocating straight hook 60 needle, it is to be understood that except as defined in the claims the invention is not limited to any particular machine or class of machines, or to any particular construction or arrangement of parts.

65 Having explained the nature and object of

the invention, and having described a machine embodying the same in its preferred form, what is claimed is:

1. A shoe sewing machine, having, in combination, a needle, a work support, a presser foot, mechanism controlled by the thickness of the work for imparting a variable stroke to the needle, a work feeding awl and connections between the needle and awl maintaining the awl under positive control 70 throughout its feed and return stroke and acting to impart a constant feeding stroke to the awl regardless of variations in the needle stroke. 75

2. A shoe sewing machine, having, in combination, a needle, a needle bar, a work support, a presser foot, means for reciprocating the needle bar, a feeding awl, an awl carrier, a moving cam and suitable connections between the cam and the awl carrier 80 for moving the awl toward and from the work, and connections between the awl carrier and needle bar for imparting feed and return strokes to the awl. 85

3. A shoe sewing machine, having, in combination, a needle, a needle bar, a work support, a presser foot, means controlled by the thickness of the work for imparting a variable stroke to the needle bar, a feeding awl, an awl carrier, a cam and suitable connections 90 for moving the awl toward and from the work, and connections between the needle bar and awl carrier acting to impart a constant feed and return stroke to the awl regardless of variations in the needle stroke. 95

4. A shoe sewing machine, having, in combination, a needle, a needle bar, a work support, a presser foot, means controlled by the thickness of the work for imparting to the needle bar a stroke variable at one limit 100 only, a feeding awl and connections between the needle bar and awl for imparting feed and return strokes to the awl, comprising a link movable to a dead center as the needle reaches the variable limit of its stroke. 110

5. A shoe sewing machine, having, in combination, a needle, a needle bar, a work support, a presser foot, means controlled by the thickness of the work for imparting to the needle bar a stroke variable at one limit 115 only, a feeding awl, an awl carrier, an actuating lever connected with the awl carrier, a second lever, a link connecting said levers, and a link connecting said second lever and the awl carrier arranged to move to a dead center as the needle reaches the variable limit of its stroke. 120

6. A shoe sewing machine, having, in combination, a needle, a needle bar, mechanism for actuating the needle bar, a feeding awl, 125 an awl carrier, a cam and suitable connections for actuating the awl carrier to move the awl toward and from the work, and connections between the needle bar and awl carrier for imparting feed and return move- 130

4
ments to the awl comprising an actuating lever, an adjustable block-and-slot connection between said lever and the awl carrier, a second lever, a link connecting said levers and a link connecting said second lever and the needle bar.

5
7. A shoe sewing machine, having, in combination, a needle, a needle bar, a work support, a presser foot, mechanism for reciprocating the needle bar, a work feeding awl, an awl carrier, connections between the needle bar and awl carrier acting to impart feed and return strokes to the awl, and arranged to maintain the awl under positive 10 control throughout its feed movement, and means independent of the needle mechanism

for actuating the awl carrier to move the awl toward and from the work.

8. A shoe sewing machine, having, in combination, a needle, a needle bar, a work support, a presser foot, means for reciprocating the needle bar, a work feeding awl, and mechanism for actuating the awl constructed and arranged to maintain the awl under positive control throughout its movements comprising a connection between the needle bar and the awl for moving the awl from the needle bar. 20 25
